UNITED STATES PATENT OFFICE.

FRANK W. BRAINERD, OF CHICAGO, ILLINOIS.

WIRE-BARBING MACHINE.

SPECIFICATION forming part of Letters Patent No. 310,178, dated January 6, 1885.

Application filed March 19, 1884. (No model.)

To all whom it may concern:

Be it known that I, FRANK W. BRAINERD, a resident of Chicago, in the county of Cook and State of Illinois, have invented certain new and useful Improvements in Wire-Barbing Machines; and I do hereby declare the following to be a full, clear, and exact description of the invention, such as will enable others skilled in the art to which it pertains to make and use the same.

My invention is an improved wire-barbing machine adapted to the manufacture of various forms of barbs, and so constructed that it wraps both ends of the barb about the main wires simultaneously.

The form, construction, and operation of the machine are fully explained and described in the following specification, and shown in the accompanying drawings, in which—

- 20 Figure 1 is a plan of the machine; Fig. 2, a side elevation thereof, looking in the direction indicated by the arrow c' , Fig. 1, the cutting mechanism being removed, and also all that part of the machine outside of the line $x'y'$;
25 Fig. 1; Fig. 3, a front elevation of the machine, looking in the direction indicated by the arrow c , Fig. 1, that part of the machine in front of the line $x'y$, Fig. 1, being removed; Fig. 4, a central vertical section (through the 30 line of the main wires) of the wire-supporting spindle and the sleeves mounted thereon; Figs. 5, 6, and 7, front elevations of the spindle and sleeves, showing successive steps in the wrapping of a barb; Fig. 8, a top view of the sleeves and spindle, showing a barb-wire fed between the main wires and ready for wrapping; and Fig. 9, a side elevation looking in the direction indicated by the arrow c'' , Fig. 6, showing the sleeves and spindle and a completed barb formed on the main wires.

In these views, A is the bed of the machine; B', the main shaft, to which power is applied by means of the pulley G; and B, a side shaft at right angles to the main shaft and connected therewith by miter-gears. On the main shaft is rigidly mounted a cam, C', which actuates the knife-carrying lever R, and on the shaft B are mounted two cams, C C', which communicate motion to the two vertically-reciprocating segment-carrying levers D D', respectively, as hereinafter set forth. Near the

center of the bed is a stationary post or support, J, bolted to the bed and supporting a cylindrical spindle, Z, which is either keyed to the post, as shown in Fig. 4, or formed integrally therewith. The spindle extends forward from the post a sufficient distance to make room for the other working parts, and its axis is a horizontal line parallel to the side shaft, B. The spindle is longitudinally pierced by two perforations for the passage and support of the two main wires $w w'$ to be barbed.

On the spindle Z is mounted a sleeve, L, provided with a pinion, I', which lies immediately in front of the post J, and on the sleeve 65 L is mounted a second sleeve, M, provided with a pinion, I, which lies immediately in front of the pinion I'. The sleeve L turns freely on the spindle Z, and the sleeve M turns freely on the sleeve L, and the front faces of 70 the spindle and the two sleeves are flush. The sleeve M is journaled in a post, J', bored out to receive it, and bolted to the bed of the machine.

The construction and relation of the parts 75 are such that the sleeve L may be slipped over the spindle, the sleeve M over the sleeve L, and the bearing in the post J' over the sleeve M, and upon bolting the last-named post to the bed it serves to support the sleeves and 80 spindle, and also to prevent longitudinal motion of the sleeves on the spindle. The pinion I' engages with a segmental gear, K', and the pinion I with a second segmental gear, K, the segments being formed integrally with two 85 vertically-reciprocating levers, D' D, pivoted on a suitably-supported shaft, T. The outer ends of the levers are provided with anti-friction rollers $a' a$, the first-named roller, a' , resting on the upper face of the cam C', already 90 mentioned, while the other roller, a , rests against the lower face of the cam C. Suitable springs, S' S, hold the rollers constantly in contact with the surfaces of the respective cams, and the rotation of the shaft B thus 95 imparts vertical reciprocal motion to the levers D' D and segments K' K. The cam C forces the segment K upward and rotates the sleeve M in the direction indicated by the arrow on its face in Fig. 5, and the cam C' forces 100 the segment K' downward and rotates the sleeve L in the opposite direction, as indi-

cated by the arrow on its face in the same figure. The inner sleeve, L, is provided with an ordinary wrapping-pin, N, set in its front face, and the outer sleeve, M, is provided 5 with a wrapping-finger, N', whose base is rigidly attached to the outer edge of the face of said sleeve, while its point lies nearer the main wires and in front of the face of the sleeve L. (See Fig. 5.) The space between 10 the face of the sleeves and spindle and the finger N' is sufficient for the pin N and the end of the barb wrapped by said pin to pass under the finger without striking. (See Fig. 8.)

At the side of the bed opposite the shaft B 15 is a suitable barb-feeding mechanism adapted to feed a barb-wire between the main wires and in front of the sleeves and spindle, and between the barb-feeding device and the main wires is a cutting mechanism consisting of one 20 stationary knife attached to the bed and one movable knife attached to the rocking lever R, which is actuated by the cam C", as hereinbefore set forth.

As the feeding and cutting devices shown 25 are old, no particular description of them is necessary, and this is especially true since they are both shown and described in the patent of D. C. Stover, of May 29, 1883. No main-wire feed is shown, but any suitable intermittent feed may be used, the main wires being fed in the direction indicated by the arrow c", Fig. 1.

The operation of the machine in making a barb is as follows: The sleeves L, M and the 30 pin N and finger N' being in the positions shown in Figs. 5, 8, the barb-wire w" is fed between the main wires w w', in front of the sleeves and spindle and under and in contact with the pin N and the point of the finger N'. 35 Immediately after the feeding of the barb the sleeve L is rotated four hundred and fifty degrees, or one and one-fourth revolution, in the direction indicated by the arrow on its face in Fig. 5, wrapping the free end f' of the barb to 40 the position shown in Fig. 6. At the instant when the sleeve L has rotated one hundred and eighty degrees and the free end of the barb is in the position shown in dotted lines in Fig. 6, the barb is severed by the cutting device, and 45 the sleeve M rotates two hundred and seventy degrees in the direction indicated by the arrow on its face in Fig. 5, wrapping the severed end w" of the barb to the position shown in Fig. 7. In other words, the free end f of 50 the barb is wrapped one hundred and eighty degrees, and both ends are then wrapped two hundred and seventy degrees at the same time in opposite directions, thus completing the barb. The barb shown is one to whose manu- 55 facture this double-sleeve device is especially adapted; but it is evident that it may be used in the making of other barbs which vary from this one only in the number of degrees through which the respective ends are wrapped. In 60 the making of any barb both sleeves may begin to wrap at once, if desired, or they may com-

mence wrapping at any desired interval of time. I think it best, however, for the sleeve which has the greater wrap to make to commence first and rotate through an arc equal 70 to the difference between the wraps to be made by the two sleeves, respectively. At this point the other sleeve should begin wrapping, and both should continue until the completion of the barb. If found necessary, the wrapping-finger N' may be provided with a lip projecting downward in front of the barb, as shown in dotted lines in Fig. 5. I have found that a slight groove in the end of the finger is sufficient, but the depending lip might give additional security against the escape of the barb-wire. In some forms of barbs the wrap is nearly all made from the free end, which must therefore be longer than the end f shown in these drawings. In such cases the base of the finger N' may extend out beyond the edge of the face to which it is attached, in order to permit the free end to pass under it without striking, as indicated by dotted lines in Fig. 7. It can be thus extended without interfering 90 with the other parts of the machine, since the stationary knife is in front of the barb-wire, in the position shown by dotted lines in Fig. 8, and the finger N' will pass in rear of the knife, no matter how much lateral extension it may 95 have.

I am aware that a stationary spindle longitudinally perforated for the passage of two main wires is a common element in wire-barbing machines, and that a single sleeve rotating 100 on a spindle is old in the art. It is also true that the cam and segment mechanism used to rotate either of the sleeves shown in these drawings has no novelty; and I do not therefore claim any of these features; but, 105

Having described my invention, what I claim as new, and desire to secure by Letters Patent, is—

1. In a wire-barbing machine, the combination of a stationary main-wire-supporting 110 spindle, a sleeve rotating freely on said spindle, a second sleeve rotating freely on said first-mentioned sleeve, wrapping devices attached to the front faces of said sleeves, respectively, and means, substantially as shown and de- 115 scribed, for rotating said sleeves.

2. In a wire-barbing machine, the combination of a stationary spindle longitudinally perforated for the passage and support of two main wires, an inner sleeve rotating freely on 120 said spindle, an outer sleeve rotating freely on said inner sleeve, suitable wrapping devices attached to the front faces of said sleeves, means for feeding a barb-wire across and between said main wires in front of said sleeves 125 and in contact with said wrapping devices, means for severing said barb-wire between the feeding mechanism and the main wires, and means for rotating said sleeves, respectively, whereby both ends of the severed barb are 130 wrapped about said main wires at the same time.

3. The combination of the spindle Z, sleeve L, rotating on said spindle, sleeve M, rotating on said sleeve L, wrapping-pin N, attached to the front face of the sleeve L and adapted to 5 wrap the free end of a barb-wire about the main wires and against the face of the spindle, and the wrapping-finger N', having its base attached to the front of the sleeve M at a suitable distance from the center to permit the 10 free end of the barb to pass under it without striking, while its point is sufficiently near the center to adapt it for wrapping the severed end of the barb about the main wires, substantially as shown and described, and for the 15 purpose set forth.

4. The combination of the spindle Z, the sleeve L, mounted on said spindle, sleeve M, mounted on said sleeve L, and bearing J, in which said sleeve M is journaled, all con-

structed and combined substantially as shown 20 and described, and for the purpose set forth.

5. The combination of the spindle Z, sleeves L M, pinions I' I, mounted rigidly on said sleeves, respectively, geared segments K' K, engaging with said pinions, respectively, oscillating levers D' D, formed integrally with 25 said segments, respectively, and cams C' C, actuating said levers, respectively, whereby said sleeves are rotated reciprocally, substantially as shown and described, and for the purpose 30 set forth.

In testimony whereof I have signed this specification in the presence of two subscribing witnesses.

FRANK W. BRAINERD.
